US0D1065355S

(12) **United States Design Patent** (10) Patent No.: **US D1,065,355 S**
(45) Date of Patent: ** Mar. 4, 2025

(54) **GAME BATH STOOL**

(71) Applicant: **Jinhua Gica Baby Products Co., Ltd.**,
Jinhua (CN)

(72) Inventor: **Xiaoyu Zhang**, Jinhua (CN)

(73) Assignee: **Jinhua Gica Baby Products Co., Ltd.**,
Jinhua (CN)

(**) Term: **15 Years**

(21) Appl. No.: **29/968,704**

(22) Filed: **Oct. 17, 2024**

(30) **Foreign Application Priority Data**

Sep. 20, 2024 (CN) 202430600542.7

(51) LOC (15) Cl. **06-01**

(52) U.S. Cl. ..... USPC **D6/333**

(58) **Field of Classification Search**

USPC D21/473, 474, 475, 477, 352, 519, 521;
D6/333, 382, 339, 715; D23/278
CPC A47D 1/00; A47D 13/107; A47D 15/006;
A47D 15/00; A63H 33/006

See application file for complete search history.

(57) **CLAIM**

The ornamental design for a game bath stool as shown and described.

DESCRIPTION

FIG. 1 is a perspective view of a game bath stool showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the game bath stool that form no part of the claimed design.

1 Claim, 8 Drawing Sheets
